UNITED STATES PATENT OFFICE.

WALTER PARSONS, OF BROOKLYN, NEW YORK.

NEEDLE THREADER.

Application filed January 8, 1925. Serial No. 1,252.

To all whom it may concern:

Be it known that I, WALTER PARSONS, a subject of the King of England, and a resident of the city of New York, borough of Brooklyn, in the county of Kings and State of New York, have invented a new and Improved Needle Threader, of which the following is a full, clear, and exact description.

This invention relates to a needle threading device. The main object of the invention is to provide a simple and efficient device whereby the needle can be threaded merely by dropping it into a simple chute and then quickly and easily manipulating the thread with respect to the needle, through which simple manipulation the needle becomes threaded.

Another object concerns the provision of means whereby the needle when dropped into the chute will automatically seat itself in the proper position to receive the thread and be threaded without any necessity on the part of the operator to hold the needle in a particular position.

A further object concerns the provision of simple and efficient means whereby merely placing the thread on the needle and exerting a slight pressure thereagainst will cause the threading action to take place, after which nothing remains to be done but to withdraw the needle from the device.

A still further object concerns the provision of a device which comprises a very few simple parts which can be economically manufactured and assembled.

The invention is illustrated in the drawings, of which—

Figure 1 is a perspective view of the device;

Fig. 2 is a vertical section therethrough showing the needle in the position it assumes as it is dropped into the chute;

Fig. 3 is a vertical section showing the needle about to be threaded;

Fig. 4 is a similar section showing the needle with the thread drawn therethrough;

Fig. 5 is a section taken on the line 5—5 of Fig. 2;

Fig. 6 is a perspective view of the end of the needle showing the thread drawn through in a loop; and

Fig. 7 is a similar view showing the thread passing through the needle in a single strand.

The form of the invention shown in the drawings is a preferred form, although it is understood that modifications in the construction and arrangement of the parts and in the character of the materials used may be adopted without departing from the spirit of the invention as set forth in the appended claims.

The invention as shown in the drawings comprises a metal plate or frame 10 from the upper portion of which a chute 11 extends. This chute has a lower front wall 12 against which the eye of a needle 13 bears. The chute is broken away along that portion adjacent the front wall so that the needle can be removed therefrom.

The bottom of the chute is formed of a depressible plate 14 forming part of a spring member 15 which is attached to the frame 10. The spring plate is curved at its forward end, as at 16 in Fig. 5, in the form of a loop having a tapered opening therein which increases in width toward the front end which lies adjacent the curved wall 12. As the needle 13 is dropped into the chute 11 the end containing the eye 17 will strike this depressible plate 14 and slide forward. As it does so it rides or rests on a loop portion 16 of the plate and comes to rest against the curved wall 12. The curvature of the wall 12 and the shape of the loop portion 16 will cause the eye of the needle to be disposed in a horizontal plane immediately over a hook 18 fastened to the frame 10 and normally lying within the loop 16 just below the top edge thereof. With the needle in the position shown in Fig. 2, the operator takes the thread in his hand and presses it down against the needle, which causes a depression of the plate 14, bringing the end of the hook 18 above the top of the loop portion 16, whereupon the thread

will slip under the hook. By releasing the pressure on the plate 14 this plate will immediately spring upward carrying with it the needle, but the hook portion will hold the thread and having passed through the eye of the needle will have drawn the thread therethrough. This position is illustrated in Fig. 4. Thereafter it is merely necessary to take the needle out of the chute and pull the thread sidewise, whereupon it will be withdrawn from beneath the hook. This position is shown in Fig. 6. The end of the

thread can then be drawn through the eye, whereupon it will assume the position shown in Fig. 7, ready for use.

What I claim is:—

5. 1. A needle threading device, which comprises a chute portion, a depressible plate in the bottom of the chute on which the needle is adapted to rest, and means associated with the plate and the chute to guide the 10 needle into a definite position.

2. A needle threader, which comprises a chute member, a depressible bottom plate therefor having an aperture therein, a hook disposed within said aperture and normally 15 beneath the upper surface of the plate, and means associated with the plate and the chute to guide the needle into a definite position therein.

3. A needle threader, which comprises a 20 frame having a chute member thereon, a depressible plate forming the bottom of the chute member, a front curved wall dis-

posed at the forward portion of said chute, the front of the bottom plate having a tapered aperture therein, the taper of said 25 aperture and the curvature of the front wall guiding the needle into a definite position when dropped into the chute.

4. A needle threader, which comprises a frame having a chute member thereon, a 30 depressible plate forming the bottom of the chute member, a front curved wall disposed at the forward portion of said chute, the front of the bottom plate having a tapered 35 aperture therein, the taper of said aperture and the curvature of the front wall guiding the needle into a definite position when dropped into the chute, and a hook member connected to the frame disposed within the aperture of the bottom plate to receive a 40 thread when the needle and the bottom plate are depressed.

WALTER PARSONS.
